Primary Examiner — April Rivas(74) *Attorney, Agent, or Firm* — Anglehart et al.(57) **CLAIM**

The ornamental design for a suitcase, as shown and described.

DESCRIPTION

FIG. 1 is a perspective view of a suitcase showing a first embodiment of my new design thereof;

FIG. 2 is a right-side view thereof;

FIG. 3 is a front view thereof;

FIG. 4 is a left-side view thereof;

FIG. 5 is a top view thereof;

FIG. 6 is a bottom view thereof;

FIG. 7 is a back-left side perspective view of a suitcase showing a second embodiment of my new design thereof;

FIG. 8 is a back view thereof;

FIG. 9 is a front-left side perspective view thereof;

FIG. 10 is a right view thereof;

FIG. 11 is a front view thereof;

FIG. 12 is a left view thereof;

FIG. 13 is a top view thereof; and,

FIG. 14 is a bottom view thereof.

The broken lines illustrate portions of the suitcase and form no part of the claimed designed.

1 Claim, 6 Drawing Sheets(56)
